(57) **CLAIM**

The ornamental design for the bedpan housing, as shown and described.

DESCRIPTION

FIG. 1 is a perspective front view of the bedpan housing, showing our new design;

FIG. 2 is a perspective bottom view thereof;

FIG. 3 is a top view thereof;

FIG. 4 is a bottom view thereof;

FIG. 5 is a rear view thereof;

FIG. 6 is a front view thereof;

FIG. 7 is a left side view thereof; and,

FIG. 8 is a right side view thereof.

The broken lines in the figures depict portions of the bedpan housing that form no part of the claimed design.

1 Claim, 6 Drawing Sheets
